UNITED STATES PATENT OFFICE.

WILLIAM B. LUCKE, OF WILMETTE, ILLINOIS.

BATHTUB WALL AND FLOOR JOINT.

Application filed August 16, 1926. Serial No. 129,504.

This invention relates to a means for securing bath tubs to building walls and floors in a manner to prevent leaks at such joining points after the building has settled. With the ordinary arrangement of mounting a bath tub against a wall, much difficulty is encountered in the course of time, due to a crack forming at the joint due to a change in the dimensions or settling of a building. The purpose of the present invention is to provide connecting means between the bath tub and building wall or floor which is to some degree expansible for accommodating relative movement between the wall and tub, and to seal with elastic material which will at all times prevent leakage of water past the joint. Such an arrangement is particularly desired where a shower is placed over the tub in position to spray water against the wall. Without a proper joint, water working into the wall and downwardly to the ceiling of a floor below, often necessitates expensive repairs.

This sealing and attaching means, as shown in the drawing, comprises a strip of sheet metal which is attached to the upright frame members of the wall along the rim of a bath tub. A similar strip is secured to the floor around the edge of the apron of the tub. The space between the edge of the tub and the securing strip is then filled with an elastic sealing means such as tar.

The improved bath tub attaching and sealing means is illustrated in the drawings, wherein:

Figure 1 is a plan view of a built-in bath tub showing walls in section surrounding three sides thereof.

Fig. 2 is a longitudinal sectional view of the construction shown in Figure 1; and

Fig. 3 is a transverse section of the same.

Fig. 4 is a plan view of a different style of tub than that shown in Figure 1, having a wall on one side thereof only and an apron extending around the remaining three sides.

Fig. 5 is an enlarged sectional detail taken on the line 5-5 of Fig. 4.

Fig. 6 is a sectional detail showing the floor joints and taken on the line 6-6 of Figure 4.

Fig. 7 is an enlarged sectional detail illustrating a flanged attaching plate used at the square corners of a tub such as illustrated in Figure 1.

Fig. 8 is a sectional view similar to that shown in Fig. 5 but showing a slightly modified attaching plate made of two parts.

In the different views a bath tub 1 of customary construction is shown provided with a standard form of rim 2, beveled at its edge 30 as indicated in Figures 5 and 8. The attaching plate 3 is shown formed to extend around the lower edge of the rim and otherwise to lie flat against the upright frame members 4 of the wall. The attaching plate 63 is nailed to these frame members, being perforated for this purpose as illustrated in Figure 7. At the corners the bent flange 5 of the plate is preferably partly cut away at 6 to facilitate bending of the plate into 70 the desired form at the corner. The space 7 between the attaching plates and the rim of the tub is filled with an elastic tar-like sealing substance, indicated by solid black.

The apron of the tub at its lower edge is 73 similarly connected to the floor beneath the tiling or other surfacing material. The connecting plate at this point is indicated at 8, Figure 8, and is somewhat differently formed than the plate 3 to provide a channel or recess 9 for receiving the lower edge so of the apron. This joint is likewise sealed by tar or similar elastic material 10.

The utility of the joining and sealing means is apparent since it effectually prevents water from working past the edge at the wall and floor joints.

I claim:

1. Means for attaching a bath tub to a wall and forming a seal at the joint, comprising a plate attached to the wall and extending along the rim of the tub and bent inwardly along its lower edge to engage the tub beneath the rim, and elastic sealing material between the outer edge of the tub 95 rim and the said plate.

2. A means for attaching a bath tub or similar article to a wall or floor comprising a plate extending along the edge of said article when attached to a wall or floor and formed to provide a pocket for sealing material such as tar and to extend around the inner edge of the rim or apron of the tub.

Signed at Chicago this 14th day of August, 1926.

WILLIAM B. LUCKE.
